SANITARY TOWEL.

1,072,746.

Specification of Letters Patent.

Patented Sept. 9, 1913.

Application filed June 10, 1912. Serial No. 702,701.

To all whom it may concern:

Be it known that I, ARTHUR P. LINVILLE, a citizen of the United States, residing at Richmond, in the county of Contra Costa and State of California, have invented new and useful improvements in Sanitary Towels, of which the following is a specification.

This invention relates to an improved sanitary towel.

10 The object of the present invention is to provide a towel for use particularly in public places, with a view of preventing the spread of infectious diseases; means being provided to intermittently advance unused portions of the towel into display while the preceding used area is wound within a concealed drum, and other means being provided for limiting the advance of the towel, which may be in a single piece of suitable 20 length.

It is also an object to provide a novel unreeeling means whereby a certain amount of the towel may be loosened or slackened after the soiled portion has been wound, so as to 25 permit the more ready drying of the hands or face on the clean, exposed, unused portion.

The invention consists of the parts and the construction and combination of parts as 30 hereinafter more fully described, and claimed, having reference to the accompanying drawings, in which—

Figure 1 is a front elevation of the towel apparatus partly broken away. Fig. 2 is 35 an end elevation of the same. Fig. 3 is an enlarged detail view of the restraining device. Fig. 4 is a vertical section through the drum inclosing the winding reel. Fig. 5 is a sectional detail, showing the restraining 40 pawl of the winding device.

In the drawings, 2 represents a piece of toweling of suitable length and width, which initially, when laundered and cleaned, is wound in a roll 3 on a spindle 4; the ends of 45 the spindle being deposited in suitable bearing brackets 5. The latter are rigidly mounted in the rear, permanent section 6 of an inclosing case having a cover 7 pivoted at 8, which cover may be opened about its 50 hinges to permit the insertion of a clean roll of toweling.

One end of the toweling is rolled from the roll 3 and carried diagonally forward and upward over a measuring drum 9, the spin-

dle 10 of which is mounted in bearing brackets 11 fastened to the rear section 6 of the case. The end of the toweling is then continued rearwardly over the measuring drum 9 and downwardly toward the back and out through a mouth 12 at the lower portion of the casing 6—7. The end of the toweling is then carried downwardly through a mouth 13 formed in a cylinder or casing 14 adapted to be arranged below the upper case 6—7; these cases being adapted for connection by 60 brackets 15 with a wall, portable panel or other suitable structure affording means for the convenient mounting of the towel.

The end of the towel, after it has been passed into the mouth 13 of the casing 14, 70 is appropriately connected to a winding reel 16, which is detachably mounted at its ends upon stems 17 and 18 journaled in suitable bearings 19 and 20 of the lower casing 14. The end of the stem 18 is provided with any 75 means for causing its rotation, and in the present instance I have shown a crank handle 21 whereby the spindle may be revolved at certain intervals.

Having properly arranged the towel as 80 hereinbefore described, the operation of the apparatus is as follows: By turning the crank 21, a predetermined length or section of the towel 2 is wound on the reel 16; the winding of the material on the reel causing 85 the measuring drum 9 to revolve, since the toweling is led over this drum. For the purpose of preventing the winding of more than a certain amount of material, the drum 9 is provided with a stop-lug or projection 22 at 90 some suitable location, which is adapted, when the drum is rotated in the direction of the arrow a, Fig. 3, to engage a restraining pawl or stop 23. The pawl 23 is pivoted at 24 for oscillation on a bracket or bearing 25, 95 which latter may be flexible and when pressed downwardly by a suitable handle or key 26 will carry the pawl 23 out of engagement with the projection 22 on the drum, thereupon permitting the drum 9 to revolve 100 under the tension of the toweling 2 when the crank 21 is operated. As soon as the key 26 has been momentarily depressed to release the pawl 23 it will snap into the path of the lug 22 and the further movement of the 105 drum 9 will be prevented. The diameter of the drum 9 is sufficient to permit the unwinding of a given length of toweling only.

when the crank 21 is operated to wind the towel.

- In practice the two cases 6—7 and the lower casing 14 are spaced apart a distance 5 rendering it convenient to use the exposed area of the towel 2. One revolution of the drum 9, when released by the pawl 23, will permit the unrolling of a section of towel approximately equal to the distance between 10 the upper and lower cases. However, in order to use the towel, it is necessary to slacken the wound portion, so I provide a slackening device, connected to the stem 17 on which one end of the winding reel 16 is mounted. 15 This slackening device consists of a short worm or screw 27, between the threads of which projects the end of a pawl 28, pivoted at 29 and normally under the tension of a spring 30 to swing away from the reel 16. 20 During the winding of crank 21 to unwind such a length of the towel as is permitted by the single rotation of the drum 9, the swinging pawl 28 runs idly at one end of the worm 27. As soon as further winding 25 of the towel 16 is prevented by the engagement of the stop 22 with its co-operative stop 23, then the spring 30 of the pawl 28 becomes operative to draw the pawl against the worm 27, and if a person pulls on the 30 exposed towel, a portion of the reeled material will be unwound from the reel 16; meanwhile the pawl 28 will travel across the screw 27 until further movement of the pawl is limited by a shoulder 31 at the end of the 35 spiral which will then check the unwinding rotation of the reel 16. After having wound the exposed, used area of the towel on the

reel 16 until a fresh, unused area is drawn from the roll 3, the desired amount of slack may be obtained by pulling on the towel at 40 its exposed portion so that the reel will be reversed; the reverse movement being stopped by the device 27 having the shoulder 31 which engages the pawl 28.

When the towel is practically used up and 45 wound upon the reel 16, the latter may be removed by the opening of one end of the casing 14 and a clean roll inserted by opening the cover section 7 and suitably adjusting the towel as previously described. 50

Having thus described my invention, what I claim and desire to secure by Letters Patent is—

In a device of the class described in combination, a towel wound on a roller, a 55 drum around which the towel passes, a releasable stop for said drum, said drum and stop co-operating with the towel to limit the amount of the latter that can be withdrawn at one operation, a roller upon which the 60 used portion of the towel is adapted to be wound, and means connected with said roller to allow a definite number of reverse rotations thereof, said means comprising a worm provided with a stop, and a pawl adapted to engage said stop after a limited number of 65 reverse rotations of said roller.

In testimony whereof I have hereunto set my hand in the presence of two subscribing witnesses.

ARTHUR E. LINVILLE.
